John H. Campbell,
ATTORNEY.

UNITED STATES PATENT OFFICE.

IRVING MANDEVILLE, OF NEWARK, NEW JERSEY.

LORGNETTE.

1,415,599.

Specification of Letters Patent. Patented May 9, 1922.

Application filed January 27, 1922. Serial No. 532,082.

To all whom it may concern:

Be it known that I, IRVING MANDEVILLE, a citizen of the United States, and a resident of Newark, county of Essex, and State 5 of New Jersey, have invented certain new and useful Improvements in Lorgnettes, of which the following is a specification.

This invention relates to an improved lorgnette which is of the type that has a 10 short handle somewhat in the form of a finger-piece, although it can also be in the form of the long-handled type, the short-handled form, however, being more easily operated.

15 The invention comprises a pair of lens frames which are adapted to be nested in parallel relation and side by side, and which swing apart so that they are extended to be held in front of the eyes, such extension being due to the influence of a spring. The handle acts as a catch to hold the frames together or in their folded position, and one lens frame is released when the lorgnette, 20 while grasped by means of the handle, is flipped or snapped sidewise, the temporary movement of the frames to one side releasing one lens so that it swings to extended position.

25 The invention is illustrated in the accompanying drawings, in which Figure 1 is a perspective view of a lorgnette made according to my invention. Figure 2 is a section through the catch, drawn on an enlarged scale, and Figure 3 is a perspective view of 30 the latch swung slightly apart from the lens frame that it engages.

35 The lens frames 10 and 11 are hinged together, usually through the medium of the bridge 12 which has spring hinges 13 and 14 40 to normally swing the frames apart, as shown in dotted outline in Figure 1. So far as now described the device is old and there are many types and designs of such spring-extended lorgnettes now in use.

45 The invention resides in such lorgnettes equipped with the catch releasable without necessitating the manipulation of a finger-piece or slide. The illustration shows a handle 15 hinged at 16 to one frame, as 10, and 50 mounted so that it has a limited swinging movement transversely to the plane of the frame. The handle is yieldingly held in normal position by the spring 17 in the hinge and has a latch 18 extending beyond the 55 hinge. The catch or handle is held at a slight distance from the lens frame 10 so

that the lens frame 11 can be slid under it, and is limited in its swinging movement as by the lug 19.

On the lens frame 11 is an element to engage the catch, and a convenient and inconspicuous form of engaging element can be provided by enlarging the frame slightly to form a nose 20. The parts are disposed so that the lens frames, when locked, are in alignment and closely folded side by side, as shown in Figure 1.

When the lorgnette is to be extended, the handle is firmly grasped and given a jerk or flip sharp enough to swing the assembled 70 lens frames on the hinge 16. This movement temporarily overcomes the influence of the spring 17 and the latch 18 is tripped and releases the nose 20, and the lens frame 11 snaps to its extended position before the 75 frame 10 resumes its normal position on the handle 15. It is a quick movement of all the parts, is substantially noiseless and no other manipulation than above described is necessary.

80 Of course it will be evident that the device can be operated by holding the handle in one hand and swinging the lens frames laterally until the frame 11 is released, but this method of operation requires two hands, and 85 it is therefore usually operated by the single movement while grasping only the handle.

Modifications in designs and in the proportion of the parts can be incorporated 90 without departing from the scope of the invention.

I claim:

1. A lorgnette comprising a pair of lens frames connected so that they can be extended and also assembled in parallel relation, and a handle hinged to one frame, the handle including a catch disposed so that it releases the other frame when the assembled frames are swung on the handle.

2. A lorgnette comprising a pair of lens frames connected so that one swings on the other, a handle secured to one frame and mounted thereon so that it can swing out of its normal position, and a catch on the handle to lock the other frame when the handle 105 is in its normal position.

3. A lorgnette comprising a pair of lens frames connected so that one swings on the other, and a handle hinged to one frame and yieldingly held in normal position and including a catch disposed so as to engage the other frame to lock it when in normal posi-

tion and to release it when the handle is swung.

4. A lorgnette comprising a pair of lens frames connected so that one swings on the other, a handle hinged to the outer edge of one frame and having a catch apart to engage the outer edge of the other frame, and a spring to yieldingly hold the handle in its

locking position, the handle being mounted so as to swing laterally relative to the plane of movement of the swinging frame.

In testimony that I claim the foregoing, I have hereto set my hand, this 25th day of January, 1922.

IRVING MANDEVILLE.
